GEORGE GODDU, OF WINCHESTER, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENING-INSERTING MACHINE.

1,282,809.

Specification of Letters Patent. Patented Oct. 29, 1918.

Application filed May 12, 1916. Serial No. 97,015.

To all whom it may concern:

Be it known that I, GEORGE GODDU, a citizen of the United States, residing at Winchester, in the county of Middlesex and 5 State of Massachusetts, have invented certain Improvements in Fastening-Inserting Machines, of which the following description, in connection with the accompanying drawings, is a specification, like reference 10 characters on the drawings indicating like parts in the several figures.

This invention relates to the devices employed in fastening inserting machines for 15 guiding a rand or similar strip of material to the point where fastenings are driven into it to secure it to a shoe or some part of a shoe. The invention will be herein disclosed as embodied in a mechanism designed particularly to meet the requirements of nailed 20 welt work. In a nailed welt shoe, as is well understood by those skilled in this art, the upper is lasted over an insole as in a McKay shoe and a strip of welting is then secured along the margin of the shoe bottom by nails 25 or similar fastenings driven through the welt, the upper and the insole. While this is an old and well known type of shoe, it has until recently been manufactured in only 30 relatively small quantities. Very recently, however, it has become more important from a commercial standpoint, and this fact has served to develop the weak points in the machinery by which shoes of this type have heretofore been manufactured. One of these 35 weaknesses involves the devices by which the welt is guided to the point at which it is secured to the other parts of the shoe. While many devices of this character have been proposed heretofore and various types are 40 now in use, they are all, so far as I am acquainted with them, more or less unsatisfactory due to a variety of reasons, among which may be mentioned the fact that they either do not guide the welt in such manner 45 as to insure the proper location of the welt on the upper and insole by reason of defective arrangement of the parts of the welt guide or lack of suitable adjustments or by reason of the guide exercising insufficient 50 control over the welt, or are relatively complicated in construction so as to require so many changes to enable the machines to handle the required variety of sizes and

styles of welts, that much of an operator's time is lost in making them.

It is the chief object of the present invention to devise a welt guide that will meet the practical requirements of devices of this character. The invention is directed particularly to the construction of a device of this type which shall be so arranged that all the adjustments necessary in operating on the various kinds of work can be effected quickly and easily and shall be so organized as to maintain guiding engagement with the 60 welt substantially to the point of insertion of the fastenings and thus control the welt effectively in the attachment of the same to the upper and insole.

The manner in which it is proposed to accomplish these objects will be readily understood from the following description of one embodiment of the invention and the novel features will be pointed out in the appended 65 claims.

Referring now to the accompanying drawings,

Figure 1 is a view in front elevation of a fastening inserting machine equipped with a welt guide constructed in accordance with 80 this invention;

Fig. 2 is a cross sectional view illustrating the manner in which a fastening is driven through a welt to secure it to the other parts of a shoe and showing in cross section the parts of the machine and the guiding devices adjacent to the point of insertion of the fastening;

Fig. 3 is an angular, exploded view of the welt guide and parts associated therewith;

Fig. 4 is an angular view showing the lower side of the guard plate of the machine shown in Fig. 1 with the welt guide provided by this invention attached thereto.

In the drawings the guiding devices are 95 shown applied to a machine of the type disclosed and claimed in the co-pending applications of Fred L. Mackenzie, Serial No. 137,152, filed December 15, 1916, and of George Goddu and Fred L. Mackenzie, 100 Serial No. 137,571, filed December 18, 1916, and designed to use string nails. Inasmuch as this is a commercial form of fastening inserting machine put out by the assignees of the present invention and one with which 105 the trade is familiar, no detailed descrip-

tion of it is necessary, particularly since the welt guide provided by this invention is equally applicable to loose nailing machines and many other types of fastening inserting 5 machines. For the present purposes it is sufficient to state that the fastening inserting mechanism includes a guard plate 2 having the usual hardened cap plate 4 and is provided with a passage 6 through which the 10 fastenings are driven and in which also the awl works. Fig. 2 shows a throat 8 of the fastening inserting mechanism just after it has positioned a fastening and the driver has driven this fastening into the work, the horn 15 tip which supports the work at the point of insertion of the fastening being indicated at 10.

The guard plate 2 has a long shank 12 extending backwardly by which it is secured to 20 the frame of the machine and the welt guide provided by this invention is mounted on one side of the shank portion of the guard plate. This device is best shown in Figs. 3 and 4 and comprises a part 14 having a welt 25 guiding slot 15 formed through its forward end and also having two welt edge guiding members 16 and 18 respectively. The welt W, Fig. 1, is unwound from a reel 20 on which it is coiled and is brought through 30 the slot 15 and under the cap 4 of the guard plate 2 into substantially the position in which it is shown in Fig. 2. It is especially desirable, of course, to control the position of the welt at the point where the fastenings 35 are driven through it so as to insure its accurate placement on the shoe; and the two welt edge guiding members 16 and 18 therefore are extended forward from the slot 15 under the guard plate to points opposite the 40 passage 6 through which the fastenings are driven. The upper and lower walls of the slot 15 of course guide the top and bottom faces of the welt and position the welt vertically, while the members 16 and 18 position 45 the welt laterally with reference to the guard plate. These parts coöperate with the work at the instant the fastening is being driven, to surround the welt on all sides adjacent to the point of insertion of the fastenings as clearly shown in Fig. 2, so that if 50 these members are properly adjusted and the work is properly presented to the machine there is no possibility of attaching the welt improperly to the shoe.

55 It will be noted that the welt guiding slot 15 points toward the lower face of the guard plate 2 so that it directs the welt toward the point of insertion of the fastenings. Since the members 16 and 18 extend away from 60 this slot in the direction of the feeding movement of the welt they are operative to guide the welt after it has passed through the slot 15. The position of the welt thus is controlled from the time it enters the welt guide 65 until it is secured to the shoe.

Inasmuch as it is sometimes desirable to replace the welt edge guiding member 16 with a similar part of different shape or dimensions, and since this part wears out more rapidly than the other parts of the 70 device, I prefer to secure this member removably to the part 14 rather than to make it integral with said part. For this purpose the end face of the part 14 is grooved to receive a tongue with which the member 16 is 75 provided and this member is secured to the part 14 by a screw 22.

It is, of course, necessary to use welts of different widths on different kinds of work, and in order to provide for the proper guiding of these various widths of welts, the welt edge guiding member 18 is mounted for adjustment toward and from its companion member 16. In the construction shown, the member 18 extends through the welt guiding slot 15 and is provided with a shank 24 which is slotted to receive a screw 26 that clamps this member adjustably to a lug 28 projecting upwardly from the part 14, as clearly shown in Fig. 3. This construction 90 thus provides for a relative adjustment of the two members 16 and 18 to vary the distance between them. The location of the adjustable edge guiding member 18 in the slot 15 is of advantage in maintaining this 95 member in the same plane as its companion member 16, while the clamping screw 26 is loosened and its adjustment is being effected, thus preventing any displacement of this member other than that desired while the 100 adjustment is being made.

It will readily be appreciated that the construction above described, while very simple, still performs all the functions required of a device of this character and that 105 the several adjustments can be easily and quickly made. It will be noted that one adjustment only is necessary for any single change in conditions; that is, it is necessary merely to adjust the member 18 to provide 110 for a change in the width of the welt used, or to adjust the member 14 if it is desired to change the distance from the edges of the welt at which the fastenings are inserted.

It is not only necessary to make provision 115 for adjusting the device for various widths of welts but also to provide for adjusting the welt edge guiding parts relatively to the passage 6 in a direction transverse to the direction of movement of the welt through slot 15 for the purpose of varying the distance from the edges of the welt at which the fastenings will be inserted. To this end the part 14 is provided with two slots through which machine screws 30 extend 120 and clamp this part to one edge of the shank 12 of the guard plate. Inasmuch as both the welt edge guiding members are mounted on the part 14 any change in the 125 adjustment of this part does not disturb 130

the adjustment made for the width of the welt. In other words, all the welt guiding parts are adjustable as a unit. At the same time any change in the relative adjustment 5 of the edge guiding members requires no change in the adjustment of the part 14 unless it is also desired to change the distance at which the fastenings will be inserted from the left hand edge of the welt as the 10 parts are seen in Fig. 2.

In order to guide the shoe properly with reference to the passage 6 in the guard plate and to the welt guiding members, an edge gage 32 is provided which bears on 15 the upper of the shoe opposite the edge of the insole. This gage may be of any suitable form but, in the machine shown, it consists of a roll 32 mounted to rotate freely on a stud 34 projecting upward from the forward end of bracket plate 36. As clearly 20 shown in Fig. 2, the upper forward edge of this roll overlaps the inner welt edge guiding member 18 so that it coöperates with the welt guide in positioning the welt properly at the point of insertion of the fastenings. 25

In machines of this general type the work is fed forward by an awl with which the machine is equipped and which advances the 30 work step by step between successive fastening inserting operations in a direction parallel to the direction of length of the passage 6 in the guard plate. It is sometimes desirable to change the position of the edge 35 gage 32 with reference to the path of movement of the awl in a direction parallel to this path, particularly in changing from broad toed shoes to those having pointed toes or vice versa. For this purpose the 40 bracket 36, which carries the roll 32, is provided with a series of teeth that interlock with similar teeth on the lower face of a slide 38, and these two parts are secured together by a bolt 40 that projects through 45 a slot formed in the bracket 36 and which extends in a direction parallel to the teeth. These teeth lie parallel to the direction of the feeding movement of the work so that the gage 32 may be adjusted parallel to this 50 path and then secured in an adjusted position by the bolt 40.

This edge gage also is mounted for adjustment in a direction at right angles to that of the adjustment just mentioned; that 55 is, at right angles to the path of feeding movement of the work. This adjustment, as is well understood by those skilled in this art, is desirable for the purpose of effecting a relative displacement of the shoe and the 60 guard plate 2 while the welt is being attached to certain parts of the shoe. For instance, in order to have the welt project the same distance beyond the upper at all parts of the shoe, it obviously is necessary to have 65 the gage 32 occupy a different position when

the machine is attaching the welt to the fore part of the shoe from that which it occupies while the welt is being attached to the shank portion of the shoe. To this end the slide 38, which lies just below the shank 70 12 of the guard plate, is clamped by means of a bolt 46 extending through a slot 48 in the slide, to a short rack bar 44 that lies on the upper face of the shank 12. A depending part 50 of this rack bar is located in the 75 slot 52 of the shank 12 and spaces the parts 44 and 38 apart sufficiently to allow them to slide freely on the shank 12 longitudinally of the slot 52, which, as shown in Fig. 3, lies at right angles to the direction of the 80 feeding movement of the work. For the purpose of effecting the adjustment of the gage 32 conveniently, a small pinion (not shown) is mounted to mesh with the teeth of the rack 44 and is arranged to be rotated 85 by a movement of a handle 54 (see Fig. 1) which is located within the convenient reach of the operative.

By swinging this handle the pinion slides the rack 44, and with it the gage 32, toward 90 or from the passage 6 in the guard plate. The extent of this adjustment is controlled by two stops 56 and 58, respectively, and by a shoulder 60 on the slide 38. The stop 58 is secured by a bolt 62, projecting through a 95 slot formed in the stop, to the edge of the shank 12 of the guard plate and consequently is stationary. The shoulder 60, by engaging the rear face of this stop limits the forward movement of the gage 32; while the stop 56 100 engages the forward face of the stop 58 upon the backward movement of the slide 38 and thus limits the rearward movement of the gage 32. A bolt 64 projecting through a slot formed on the stop 56 secures this member 105 adjustably to the slide 38. Inasmuch as both the stops 56 and 58 are adjustable in directions parallel to the direction of the adjusting movement of the edge gage and since the slide 38 also is adjustably secured to the rack 110 bar 44, any desired range of movement of the gage 32 may be obtained.

While the embodiment of the invention now preferred by me has been herein shown and described, it is obvious that the invention may be embodied in other forms differing in detail from that herein disclosed but still retaining its essential characteristics. 115

Having thus described my invention, what I claim as new and desire to secure by Letters Patent of the United States is:

1. In a fastening inserting machine, the combination with a guard plate having a passage through which the fastenings are driven, of a welt guide mounted adjacent 125 to said guard plate, said welt guide being constructed and arranged to guide the welt by engagement with opposite edges thereof to the point of insertion of the fastenings, and being mounted for adjustment relatively 130

- to said guard plate as a unit in a direction transverse to the direction of movement of the welt through said guide.
2. In a fastening inserting machine, the combination with a guard plate having a passage through which the fastenings are driven, of a welt guide mounted beside said guard plate, said guide having a welt guiding slot pointing toward the lower side of said plate and having parts arranged to engage opposite edges of the welt after it has passed through said slot and guide it to the point of insertion of the fastenings, said welt guide being constructed and arranged for the relative adjustment of said parts to vary the distance between them and for simultaneous adjustment with reference to said passage transversely of the path of movement of the welt through the guide.
3. In a fastening inserting machine, the combination with a guard plate having a passage through which the fastenings are driven, of a welt guide mounted adjacent to said guard plate and having two opposed welt edge guiding members extending under said plate on opposite sides of said passage and mounted for simultaneous and relative adjustments in a direction transverse to the direction of movement of the welt through said guide.
4. In a fastening inserting machine, the combination with a guard plate provided with a passage through which the fastenings are driven, of a welt guide mounted on said plate for adjustment as a unit in a direction transverse to the path of movement of the welt through the guide, said guide having parts constructed and arranged to guide opposite edges of the welt to points substantially opposite to the point of insertion of the fastenings, one of said edge guiding parts being mounted for adjustment toward and from its companion part.
5. In a fastening inserting machine, the combination with a guard plate provided with a passage through which the fastenings are driven, of a welt guide separate from the guard plate and comprising a part provided with a welt guiding passage and two members mounted on said part, said members being shaped and positioned to guide the opposite edges of the welt after it has passed through said passage and being supported for relative adjustment to vary the distance between them.
6. A welt guide, comprising a part having a welt guiding slot formed therethrough, a welt edge guiding member secured to said part, and another welt edge guiding member projecting through said slot and mounted on said part for adjustment toward and from the first member, said members projecting away from said part in the direction in which the welt is moved through said guide, whereby they are operative to guide the opposite

edges of the welt after it has passed through said slot.

7. In a fastening inserting machine, the combination with a guard plate provided with a passage through which the fastenings are driven, of a welt guide separate from the guard plate and comprising a support extending along one side of the guard plate transversely of said passage, said support having two opposed welt edge guiding members mounted thereon and extended under said plate on opposite sides of said passage and being constructed and arranged to guide opposite edges of the welt to points substantially opposite to the point of insertion of the fastenings, and a gage overlapping one of said members and positioned to engage the upper of a shoe while the welt is being attached to it.

8. In a fastening inserting machine the combination with a guard plate having a passage through which the fastenings are driven, of a welt guide mounted adjacent to said plate and comprising a member constructed and arranged to support the welt and two opposed welt edge guiding members extending from said welt supporting member under said plate on opposite sides of said passage, and constructed and arranged to guide opposite edges of the welt to points substantially opposite to the points of insertion of the fastenings, a gage positioned adjacent to one of said members for engagement with the upper of the shoe to which the welt is being attached, and means supporting said gage for adjustment, in directions both parallel to and transversely of the direction of movement of the welt past said guard plate.

9. In a machine for fastening a welt to the upper and sole of a shoe, the combination with a guard plate provided with a passage through which the fastenings are driven, of a welt guide mounted for adjustment as a unit relatively to the guard plate and having two opposed welt edge guiding members extending under said plate on opposite sides of said passage and being constructed and arranged to guide opposite edges of the welt to points substantially opposite to the point of insertion of the fastenings, and a gage overlapping one of said members and positioned to engage the upper of a shoe while the welt is being attached to it.

10. In a machine for fastening a welt to the upper and sole of a shoe, the combination with a guard plate provided with a passage through which the fastenings are driven, of a welt guide having two opposed welt edge guiding members extending under said plate on opposite sides of said passage and being constructed and arranged to guide opposite edges of the welt to points substantially opposite to the point of insertion of the fastenings, and a gage positioned to engage the

- upper of a shoe while the welt is being attached to it, said welt guide being mounted for adjustment as a unit relatively to the guard plate and gage, and said gage being 5 mounted for adjustment relatively to the guard plate and welt guide, whereby upon adjustment of the welt guide the spacing of the driven fastenings relatively to the edges of the welt is changed without affecting the 10 spacing of the fastenings from the edge of the sole, and upon adjustment of the gage the spacing of the fastenings from the edge of the sole is changed without affecting the spacing thereof relatively to the edges of the 15 welt.
11. In a fastening inserting machine, the combination with a guard plate having a passage through which the fastenings are driven, of a welt guide mounted adjacent 20 to said guard plate and having two opposed welt edge guiding members extending under said plate on opposite sides of said passage and mounted for common and relative adjustments in a direction transverse to the 25 direction of movement of the welt through said guide, and a gage for the upper adjustably mounted relatively to the guard plate and guide.
12. In a fastening inserting machine, the 30 combination with a guard plate having a passage through which the fastenings are driven and formed with a shank extending a relatively long distance from the said passage for securing the guard plate to the 35 frame of the machine, of a welt guide slidably mounted on the shank of the guard plate for adjustment thereon and comprising two opposed welt guiding members extending under said plate on opposite sides of said passage, 40 of said 45 50 55 60 65 70 75 80 85 90 95 100 105 110 115 shank, and means for securing said guide in adjusted position on said shank.
13. In a fastening inserting machine, the combination with a guard plate having a 45 passage through which the fastenings are driven and formed with a shank extending a relatively long distance from the said passage for securing the guard plate to the frame of the machine, of a welt guide slidably mounted on the shank of the guard plate for adjustment thereon and comprising two opposed, relatively adjustable, welt guiding members extending under said plate on opposite sides of said passage, and means 55 for securing said guide in adjusted position on said shank.
14. In a fastening inserting machine, the combination with a guard plate having a 60 passage through which the fastenings are driven and formed with a shank extending
- a relatively long distance from the said passage for securing the guard plate to the frame of the machine, of a welt guide slidably mounted on the shank of the guard plate for adjustment thereon and comprising two opposed welt guiding members extending under said plate on opposite sides of said passage, means for securing said guide in adjusted position on said shank.
15. In a fastening inserting machine, the combination with a guard plate having a passage through which the fastenings are driven and formed with a shank extending a relatively long distance from the said passage for securing the guard plate to the frame of the machine, said shank having a slot in substantially transverse alinement with the said passage, of a welt guide slidably mounted on the said shank for adjustment thereon and comprising two opposed welt guiding members extending under said plate on opposite sides of said passage, a gage for the upper, and means supporting the gage and slidably mounted in said slot for adjusting said gage.
16. In a fastening inserting machine, the combination with a guard plate having a passage through which the fastenings are driven and formed with a shank extending a relatively long distance from the said passage for securing the guard plate to the frame of the machine, said shank having a slot in substantially transverse alinement with the said passage, of a welt guide slidably mounted on the said shank for adjustment thereon and comprising two opposed welt guiding members extending under said plate on opposite sides of said passage, a gage for the upper, a rack slidably mounted in the slot of the shank for supporting and actuating said gage and means for operating said rack to adjust said gage.
17. In a machine for inserting fastenings, in combination, a guard plate, a welt guide, a support, a gage for the upper located below the welt guide, a gage carrier movable beneath the support, a rack mounted to slide on the support in a direction transverse to the direction of movement of the welt in the guide, means for operatively connecting the gage carrier and rack, means for actuating the rack, and adjustable means for limiting the range of movement of the gage carrier.

In testimony whereof I have signed my name to this specification.

GEORGE GODDU.
